UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

CONTINUOUS CONVEYER.

1,144,323.

Specification of Letters Patent. Patented June 22, 1915.

Application filed September 30, 1910. Serial No. 534,699.

To all whom it may concern:

Be it known that I, HENRY A. CARPENTER, a citizen of the United States, residing at Sewickley, in the county of Allegheny and

5 State of Pennsylvania, have invented a new and useful Improvement in Continuous Conveyers, of which improvement the following is a specification.

10 My invention relates to improvements in endless conveyers, and more particularly the general link and drive structural features thereof.

15 The invention is designed more particularly for use in gas retort houses and particularly in connection with the transfer of coke as it is discharged from the retorts to a suitable point. As will be understood, the retort houses of gas plants of considerable capacity are of considerable length while

20 the coke discharged from the retorts is generally incandescent. As a result, an endless conveyer adapted for this purpose must have certain characteristics to provide for efficient service. As examples, the conveyer must be

25 relatively light in weight cross-sectionally in order that the tendency to sag under its own weight will be reduced to a minimum; the carrying surface should be substantially flat to prevent the coke from being banked up

30 thereon; the conveyer should not be so rigid in arrangement as to tend to break the coke as it falls onto the conveyer; the conveyer should be of a material which will not be injuriously affected by the heat of the incandescent coke. To meet these conditions

35 the conveyer is formed in a particular manner as to link construction, and the driving means is so formed as to provide for placing the driving strain substantially throughout

40 the width of the conveyer.

To these and other ends, the nature of which will be readily understood as the invention is hereinafter disclosed, said invention consists in the improved construction

45 and combination of parts hereinafter fully described, illustrated in the accompanying drawings, and more particularly pointed out in the appended claims.

50 In the accompanying drawings, in which similar reference characters indicate similar

parts in each of the views, Figure 1 is a side elevation of a portion of the conveyer and a driving sprocket, a portion of the trough being shown in section. Fig. 2 is a sectional view on line II—II of Fig. 1. Fig. 55 3 is an edge view of a portion of the conveyer, parts being broken away. Fig. 4 is a plan view of the parts shown in Fig. 3, parts being broken away for clearness.

In the drawings, the conveyer is shown as 60 formed of a plurality of endless bands, arranged generally in a preferred manner, and connected in such arrangement by pins or rods, preferably headed. The bands are preferably of relatively thin sheet metal; 65 the ends of a band may be secured together in suitable manner, as by rivets. The preferred arrangement is shown in Figs. 3 and 4, in which 4, 4, 4, 4 indicated two pairs of bands, each pair being alined laterally of the conveyer, with corresponding bands of the pairs arranged in alinement longitudinally of the conveyer. Pairs of bands are spaced apart laterally by an endless band 7, corresponding end portions of a pair of 70 bands and an end portion of the intervening band 7 being mounted on a pin or rod 10, preferably headed, as at 11, a separate rod or pin being provided for each end portion of alined bands 7 of the conveyer. The end 75 portions of bands partially encircle the pins or rods so that the adjacent pairs of bands 4 and band 7 will, under driving stress, provide a practically taut construction. This arrangement has the effect of providing in- 80 closed spaces 9 between successive bands 7 longitudinally of the conveyer, and spaces 6 between adjacent pairs of bands 4, these latter spaces being open opposite the edges of the band 7. 85

The conveyer is adapted to operate in connection with driving members of the character shown in Figs. 1 and 2, being in the form of sprocket wheels 1 adapted to be mounted on a shaft, not shown, and driven 95 in any suitable manner. As shown, the wheel is provided with teeth arranged staggered, positioned to coöperate with the several spaces of the conveyer, the teeth 2 entering spaces 9, and teeth 3 extending into 100

spaces 6. While the individual teeth are of ample depth, the opposite faces of a tooth are so arranged relative to the faces of adjacent teeth in advance as to limit the depth 5 to which the conveyer extends into the spaces between teeth, so that in use the teeth preferably do not project beyond the face of the conveyer to any material extent. As shown, the bands are of comparatively short length, 10 so that the teeth 3 of a lateral row and a tooth 2 are generally active as driving members at the same time, a fact which, coupled with the arrangement of the bands, is of advantage in that the driving pressure on 15 the conveyer is positive throughout the width of the conveyer, although the bands themselves are not positively held in position on the pins or rods as would be provided by causing a band to entirely surround a pin or rod. This provides for flexibility as well as efficiency, especially when employed for the purpose indicated, the conveyer readily adapting itself to the effects 20 of expansion and contraction without materially affecting the general feature of a conveying surface free from projections, producing practically a plane surface. The bands are preferably of sufficient width to provide a proper distribution of driving 25 stress. In the drawings, the bands 7 are shown as of substantially equal width to the combined width of the pair of bands 4. As will be understood, the difference in width 30 of the spaces 6 and 7 does not limit the lateral width of the teeth 3, the spaces 6 being open in a direction which permits such width 35 to be greater than the width of the spaces if desired.

It will be obvious that the particular 40 structure and arrangement of parts is such as to be especially useful in connection with an installation for the conveying of the discharged incandescent coke. As the coke is discharged from the retort, it falls on to 45 the conveyer, which, owing to the particular construction, is not so rigid as to cause the coke to be materially broken under the shock of meeting the conveyer; consequently a minimum amount of "breeze" is formed. 50 And since the conveying surface is in the form of relatively thin bands, the heat transmitted to the bands by the coke will be quickly dissipated, while the band form and particular manner of mounting on the pins 55 or rods will provide for efficient service under the effects of expansion and contraction to which the conveyer is especially subject under working conditions.

12 indicates a trough through which the 60 conveyer travels arranged relatively to the retorts, and which serves to direct the coke onto the conveyer surface.

Having thus described my invention, what I claim as new is:

65 1. In a conveyer adapted to accommodate

for heat expansion and contraction, two pairs of sheet-metal relatively flat endless bands, each pair being alined laterally with corresponding bands of a pair alined longitudinally of the conveyer, pins or rods 70 extending transversely of the conveyer through the ends of said bands, and a sheet-metal relatively flat endless connecting band mounted on the pin of opposing ends of the pairs of bands between and forming a spacing 75 member for each of said pairs, each of said bands having a width less than the width of the conveyer, the spaces at the sides and in advance and in rear of the connecting band forming tooth-reserving spaces. 80

2. In a conveyer adapted to accommodate for heat expansion and contraction, two pairs of sheet-metal relatively flat endless bands, each pair being alined longitudinally of the conveyer, pins or rods extending 85 transversely of the conveyer through the ends of said bands, and a sheet-metal relatively flat endless connecting band mounted on the pins of opposing ends of the pairs of bands between and forming a spacing 90 member for each of said pairs, each of said bands having a width less than the width of the conveyer, the spaces between the opposing ends of longitudinally alined bands of the pairs being open opposite the connecting 95 band, the bands of a pair being of a width to permit said open spaces to receive the teeth of a driving member.

3. In a conveyer adapted to accommodate for heat expansion and contraction, two pairs of sheet-metal relatively flat endless bands, each pair being alined laterally with corresponding bands of a pair alined longitudinally of the conveyer, pins or rods extending 100 transversely of the conveyer through the ends of said bands, and a sheet-metal relatively flat endless connecting band mounted on the pins of opposing the ends of the pairs of bands between and forming a spacing member for each of said pairs, each of said bands having a width less than the width of the conveyer, the spaces at the sides and in advance and in rear of the connecting band forming tooth-receiving spaces, in combination with a driving member having 105 teeth corresponding in relative positions to the teeth-receiving spaces of the conveyer, the contact driving stress extending substantially throughout the lateral width of 110 the conveyer. 115

4. In a conveyer adapted to accommodate for heat expansion and contraction, two pairs of sheet-metal relatively flat endless bands, each pair being alined laterally with corresponding bands of a pair alined longitudinally of the conveyer, pins or rods extending 125 transversely of the conveyer through the ends of said bands, and a sheet-metal relatively flat endless connecting band mounted on the pins of opposing ends of 120 130 135 140 145 150 155 160 165 170 175 180

the pairs of bands between and forming a spacing member for each of said pairs, each of said bands having a width less than the width of the conveyer, the contact of pin and band being insufficient to prevent release of contact upon placing slack in the conveyer.

In testimony whereof, I have hereunto signed my name in the presence of two subscribing witnesses.

HENRY A. CARPENTER.

In the presence of—

CLARENCE A. WILLIAMS,
JOHN H. RONEY.

Copies of this patent may be obtained for five cents each, by addressing the "Commissioner of Patents,
Washington, D. C."

It is hereby certified that in Letters Patent No. 1,144,323, granted June 22, 1915, upon the application of Henry A. Carpenter, of Sewickley, Pennsylvania, for an improvement in "Continuous Conveyers," an error appears in the printed specification requiring correction as follows: Page 2, line 80, for the compound word "tooth-reserving" read *tooth-receiving*; and that the said Letters Patent should be read with this correction therein that the same may conform to the record of the case in the Patent Office.

Signed and sealed this 27th day of July, A. D., 1915.

[SEAL.]

R. F. WHITEHEAD,

Acting Commissioner of Patents.
